United States Patent Office

Des. 195,671
Patented July 16, 1963

195,671

BREEZEWAY WALL UNIT

Arthur J. Hansmann, 222 White Sand Lane, Racine, Wis.

Filed Nov. 20, 1961, Ser. No. 67,604

Term of patent 3½ years

(Cl. D13—1)

FIG. 4

FIG. 2

FIG. 3

FIG. 1 is a side elevational view of a breezeway wall unit showing my new design, and the side opposite is the same.

FIG. 2 is an end elevational and partly sectional view taken on the line 2-2 of FIG. 1.

FIG. 3 is a sectional view taken on the line 3-3 of FIG. 1.

FIG. 4 is a reduced top plan view of that shown in FIG. 1.

I claim:

The ornamental design for a breezeway wall unit, substantially as shown and described.
